CLAIM

The ornamental design for a telephone, as shown and
described.

DESCRIPTION

FIG. 1 is a partial front and right side perspective view
of a telephone showing my new design;

FIG. 2 is a right side elevational view thereof, the left
side being a mirror image of the right side shown;

FIG. 3 is a rear view thereof;

FIG. 4 is a front view thereof;

FIG. 5 is a top plan view thereof;

FIG. 6 is a bottom plan view thereof; and

FIG. 7 is a front and right side perspective view of the
telephone in an open position.

FIG. 1

FIG.2
